STOKER

Howard P. Anderson, Erie, Pa., assignor to The Standard Stoker Company, Incorporated, a corporation of Delaware

Application September 24, 1930, Serial No. 484,084
Renewed March 23, 1934

6 Claims. (Cl. 110—101)

My invention relates generally to stokers and more particularly to locomotive stokers of the type in which fuel is scattered over the firebox in aerial paths.

5 It is an object of this invention to provide a novel stoker having an arrangement and combination of parts which will give an even and uniform distribution of fine and coarse fuel over the entire firebed area.

10 It is another object of the invention to provide a novel distributing system in which distribution of fuel over the various parts of the firebed may be independently and conveniently controlled to produce heavier or lighter firing as desired.

15 Further advantages of the invention reside in the combination and arrangement of parts in a mechanical stoker productive of a more efficient and economical distribution of fuel over a fire hereinafter more particularly described, illustrated and claimed.

A preferred and practical embodiment of the invention is illustrated in the accompanying drawings, in which

Fig. 1 is a central longitudinal vertical section 25 of a portion of a locomotive with a stoker therefor, the distributing system being shown in section;

Fig. 2 is a plan section on the line 2—2 of Fig. 1;

30 Fig. 3 is a view similar to Fig. 1 with the distributor manifold of the distributing system and the fuel feeding conduits being shown diagrammatically; and

Fig. 4 is a plan view of the structure shown 35 in Fig. 3 with parts broken away and parts in section.

A portion of a locomotive boiler firebox is represented at 10; the grates therefor at 11; the backhead of the boiler at 12 and the firing 40 opening therein at 13.

The stoking mechanism indicated generally at 14 comprises the telescoping conduit 15, an elbow conduit 16 carried from the backhead 12 by a supporting bracket 17, and a hood portion 18 45 surmounting the elbow 16 and communicating at its forward end through the discharge mouth 19 with the lower portion of the firing opening 13.

The elbow 16 terminates at its lower end in a spherical seat 20 adapted to receive the ball 50 member 21 of the conduit 15. A distributor table 22 is detachably connected to the upstanding wall 23 of the elbow 16 by suitable means such as the bolts 24, 24a, and extends forwardly from without the firebox and terminates in the firing 55 opening. Since the distributor table does not

extend into the firebox it is not subjected to the intense firebox heat, thereby increasing the service life of the distributor table.

The hood portion 18 surmounting the elbow 16 is fastened thereto by the bolts 25, and is provided with the flanges 26, 26a for attachment to the backhead by suitable fastening means, as by bolts, not shown. The hood portion comprises the outwardly flaring sidewalls 27, 28, the removable cover 29, and at the rear is provided with a detachable manifold 30 forming the backwall thereof.

60 The fuel from the telescoping conduit 15 is received in and directed forwardly and upwardly from the end of the screw conveyor 31 by the curved elbow 16 to the hood portion 18. The hood portion 18 flares laterally as it extends forwardly to form the desirable width of discharge mouth 19 through which the fuel can be most effectively discharged by the distributing means. The sidewalls 27, 28 of the hood portion are provided at their rearward ends with the laterally projecting lugs 32, 33 adapted to receive bolts 34, 35 respectively for detachably securing the manifold 30 to the hood portion.

65 The manifold 30 is provided with a main chamber 36 extending its full length and forward thereof of a plurality of independent steam chambers 37 side by side in a horizontal plane, each being supplied with steam from the main chamber 36. Steam is supplied to the main chamber by a supply pipe 38 from any suitable source, as from the locomotive boiler. Screw valves 39 are arranged to seat on the valve seats 40 so that the supply of steam from the main chamber 36 to the independent steam chambers 37 may be independently varied and controlled.

70 The steam chambers 37 are provided with the horizontally aligned jet openings 41, the intermediate jet opening being parallel with the center line of the locomotive and the jet openings on either side flaring outwardly from the intermediate jet, so that divergent blasts of steam issue from the manifold 30. These blasts of steam are directed against the rising column of fuel and force it forwardly over the distributor table 22. Five jets are shown in the drawings, but it will be obvious that the number may be varied to meet the conditions of firing.

75 The top surface 42 of the distributor table 22 inclines slightly downward from its rearward to its forward edge and is provided with a plurality of longitudinal upstanding ribs 42a. It will be understood that the terms "rear" and "front" as applied to the distributor table 22, 80

denote the rear as that portion of the table to which the fuel is delivered and the front as that portion from which the fuel is projected. The ribs 42a are highest at their forward ends 5 and taper as they extend rearwardly until they merge into the top surface 42 of the table 22. Thus it will be seen the ribs 42a incline upwardly from the horizontal as they extend forward and the spaces between the ribs incline down- 10 wardly as they extend forward. This construction permits the fine fuel to be projected forwardly between the ribs and the lumps which are too large to pass between will be combed out and projected forwardly along the top of 15 the ribs. Thus by giving the larger lumps of fuel a longer trajectory than the fines an even distribution of fines and lump fuel over the entire firebed is obtained. The ribs on either side of the center ribs flare outwardly from rear to 20 front in order to deliver fuel to the sides of the firebed.

The top deflector members 43, 43a which are fastened each to a respective sidewall of the hood portion 18 by suitable means, as by the 25 bolts 44, 44a and 45, 45a, further aid in the equal distribution of fuel over the firebed by intercepting a portion of the fuel and deflecting it to the rear corners of the firebox. The openings 46, 46a receiving the bolts 45, 45a respectively, are preferably slotted so that the inclination of the deflector members may be varied and adjusted.

In order to effect a more equal distribution of fuel over the firebed, auxiliary chambers as 47, 35 with booster jets 48 therein are formed in the distributor table 22. The booster jets 48 are given an upward inclination and open at the forward edge of the table 22 and project fuel forwardly that is too heavy to be moved to the 40 front of the firebox by the rear jets. Pressure fluid, as steam, is supplied to the auxiliary chambers 47 through pipes 49 leading from auxiliary chambers 50 in the manifold 30, and the intensity of the blasts issuing from the jets 48 is 45 regulated independently of the intensity of the blasts issuing from the jets 41 by the valves 51 cooperating with the seats 52 in the auxiliary chambers 50. Three such booster jets are provided in my preferred embodiment, but it will 50 be obvious that more jets may be added if desired. The jets are positioned each directly beneath a respective rib, so that the fine fuel, which is projected forwardly across the distributor table in the spaces between the ribs, will not come 55 in contact with the blast from the booster jets.

In operation, fuel is advanced continuously from a suitable source, not shown, by the screw 31 and is urged upwardly and forwardly through the elbow 16. The rear distributor jets strike 60 the rising column of fuel issuing from the elbow 16 and project it forwardly, the fines passing between the ribs of the distributor table and the larger lumps of fuel which are combed out by the ribs passing thereover. A portion of the 65 projected fuel is deflected to the rear corners of the firebox by the top deflector members 43, 43a, and the heavy lumps of fuel which are not given sufficient impetus by the rear jets to carry them into the firebox, fall over the forward edge of 70 the plate and are projected over the firebed by the booster jets 48.

The novel stoker and distributor arrangement constituting this invention is productive of a very even and uniform distribution of fines and lump fuel over the entire firebed area. It is 75

extremely flexible in operation, and can be conveniently manipulated to produce heavier or lighter firing at any point of the firebed area by adjusting the valves and top deflectors.

I claim:

1. In a mechanical stoker, in combination with a firebox having a backwall and a firing opening therein, a hood member communicating with the lower portion of said firing opening, a conduit elbow arranged for delivery of fuel to said hood member, a distributor table terminating at its forward end in said firing opening and forming an extension from the floor portion of said hood member, means at the rear of said hood member for projecting fuel forwardly over said distributor table, means on said distributor table arranged to separate the coarse fuel from the fines as it is projected thereover, means at the forward edge of said distributor table arranged to give added impetus to the coarse fuel and means above the fuel stream for deflecting a portion thereof to the rear corners of said firebox.

2. In a mechanical stoker, in combination with a firebox having a backwall and a firing opening therein, a hood member communicating with the lower portion of said firing opening, means for delivering fuel to said hood member, a distributor table in said firing opening, pressure fluid distributing jets at the rear of said hood member arranged to emit a plurality of horizontal blasts of pressure fluid against the fuel and across said distributor table, means on said distributor table arranged to separate the coarse fuel from the fines as it is projected thereover, and pressure fluid distributing jets formed in said distributor table arranged to emit upwardly directed blasts of pressure fluid from the forward portion of said distributor plate to give added impetus to the coarse fuel, and means for controlling the intensity of said first and second named blasts independently of each other.

3. In a mechanical stoker, in combination with a firebox having a backwall and a firing opening therein, a hood member communicating with the lower portion of said firing opening, a conduit elbow arranged to deliver fuel to said hood member in a continuous rising column, a distributor table in said firing opening, pressure fluid distributing means at the rear of said hood member for emitting a plurality of blasts of pressure fluid against said rising column of fuel and projecting it forwardly across said distributor table, means on said distributor table arranged to separate the coarse fuel from the fines as it is projected thereover, and pressure fluid distributing means formed with said distributor table for emitting a plurality of blasts of pressure fluid from the forward edge of said distributor table arranged to give added impetus to the coarse fuel.

4. The combination with a furnace of means for distributing fuel over the firebed of the furnace comprising a distributor table, distributing means rearward thereof for emitting pressure fluid against the fuel and across said distributor table, means on said distributor table arranged to separate the coarse fuel from the fines as it is projected thereover, and a separate independently controlled pressure fluid means formed with said distributor table for emitting pressure fluid from the forward edge of said distributor table arranged to give added impetus to the coarse fuel.

5. The combination with a furnace of means for distributing fuel over the firebed of the furnace comprising a distributor table, a manifold rearwardly thereof arranged to receive pressure

fluid from a source of supply and including a main chamber and a plurality of secondary chambers arranged to receive pressure fluid from said main chamber, jet outlets leading from said 5 secondary chambers for emitting pressure fluid blasts across said distributor table and a plurality of auxiliary chambers arranged to receive pressure fluid from said main chamber, said distributor table including a plurality of auxiliary 10 chambers, means for conducting pressure fluid from said manifold auxiliary chambers to said distributor table auxiliary chambers, jet outlets in the forward edge of said distributor table communicating with the auxiliary chambers thereof, 15 and means for independently controlling the fluid

pressure in each of said secondary and said auxiliary chambers.

6. The combination with a furnace of means for distributing fuel over the firebed thereof comprising a distributor table, a distributing means 80 rearwardly thereof for emitting pressure fluid against the fuel and across said distributor table, a plurality of upstanding ribs on said table extending longitudinally and inclined from the rearward to the forward portion thereof whereby 85 coarse fuel will pass over said ribs and the fines will pass between said ribs, and means in said plate directly beneath said ribs arranged to emit upwardly directed blasts of pressure fluid.
